(57) **CLAIM**

I claim the ornamental design for a food service venting plug, as shown and described.

DESCRIPTION

FIG. 1 is a perspective view of the food service venting plug. FIG. 2 is a top plan view of the food service venting plug. FIG. 3 is a front elevation view of the food service venting plug.

FIG. 4 is a bottom plan view of the food service venting plug; and,

FIG. 5 is a side elevation view of the food service venting plug with a dotted line showing the surrounding environment.

The broken line showing is for illustrative purposes only and forms no part of the claimed design.
